UNITED STATES PATENT OFFICE.

ERNESTO FUCHS, OF GUADALAJARA, MEXICO.

DOUBLE-COMPARTMENT SUBSTANCE-HOLDER.

1,033,689.

Specification of Letters Patent. Patented July 23, 1912.

Application filed March 2, 1912. Serial No. 681,107.

To all whom it may concern:

Be it known that I, ERNESTO FUCHS, a citizen of the United States of America, residing at Guadalajara, in the State of Jalisco 5 and Republic of Mexico, have invented new and useful Improvements in Double-Compartment Substance-Holders, of which the following is a specification.

This invention is an improved double compartment substance holder, adapted for use in holding condiments, such as salt and pepper, and also for using other material or substances, whether liquid or solid, the object of the invention being to provide an 15 exceedingly simple and compact device of this character, comprising a single body having a pair of compartments adapted to hold powder or liquid material, or substances, and also provided with a cap for the 20 said body having a partition which coacts with the partition in the body to form two separated compartments, and with spring-operated closures, having a common hinged mounting on the center of the cap and provided with means for closing the openings 25 in the cap, as hereinafter described and claimed.

In the accompanying drawing:—Figure 1 is a vertical central sectional view of a double compartment substance holder, constructed in accordance with my invention. Fig. 2 is a side elevation of the same, showing one of the closures open. Fig. 3 is a plan of the same. Fig. 4 is a detail sectional 35 view, showing the modified form of my invention.

My improved double compartment substance holder comprises a vessel or body 1, which is here shown as of slightly upward 40 tapered form, and provided with a centrally disposed integral partition wall 2 which divides the vessel or body into a pair of separated chambers or receptacles 3 and 4.

45 In the form of my invention shown in Figs. 1, 2 and 3, the vessel 1 is formed, near its upper open end, with a bead or flange 5, exteriorly disposed, and with a reduced, tubular upper end 6. A stud 7, which is radially 50 arranged, projects from the outer side of the said reduced tubular upper portion or end of the vessel. I also provide a cap 8 which comprises a tubular portion 9 adapted to fit on the reduced tubular upper end of the vessel, and to bear against the shoulder formed 55 by the bead or flange 5, the top of the cap

being formed by a pair of upwardly converging angularly related inclined portions 10 each of which is provided with a suitable number of openings 11. At the apex of the 60 cap, at opposite sides thereof, are a pair of medially disposed upwardly projecting lugs 12. A rod 13 connects the said lugs and extends across the cap, above the apex thereof. The cap is provided in its cylindrical portion 8 with a bayonet slot 14 adapted for engagement with the stud 7 so that the cap may be detachably secured on the upper end 65 of the vessel or body 1, as will be understood. The cap is provided on its inner side 70 with a centrally disposed depending wall or partition 15 which engages the upper edge of and is in line with the partition or wall 2 of the vessel 1. On the inclined portions 10 of the cap are closures 16 each of which is 75 provided with an integral substantially U-shaped lever arm 17. These lever arms of the closures are angularly related and the arm of one of the closures is shorter than and extends through the arm of the other as 80 is clearly indicated in Fig. 3. The arms of the closures are both pivoted on the rod 2 so that the latter forms the common pivot or pintle for both of the closures and the said 85 closures are provided on their under sides with tapered blocks or projections 18 which pass through and close the openings in the top of the cap when the closures are in closed position. These closures are normally held in closed position by means of 90 coiled springs 20 which are placed on the rod 12.

95 It will be understood from the foregoing description that by depressing the lever arm of either one of the closures the said closure may be opened so as to uncover the openings in that side of the cap and, hence, permit material, salt, pepper or other material, as the case may be, to be shaken or poured out of one compartment of the vessel and that as soon as the pressure of the finger is removed from the said lever arm, the said closure will be closed by the action 100 of its spring and prevent any further escape of the material or substance. It will also be understood that the stud and bayonet slot connection enables the cap to be readily removed from the vessel to permit the latter 105 to be replenished or cleansed.

110 In the modified form of my invention, shown in Fig. 4, the upper portion of the body 1^a of the vessel is formed with screw

threads 21 exteriorly arranged, and the cap 22 is formed with a threaded portion 23 to engage the threaded upper end of the vessel, and, hence, permit the cap to be detachably secured to the vessel. The openings in the cap and the plugs or projections of the closures may be of any suitable number and of any suitable size, according to the nature of the material or materials designed to be held by the double compartment holder.

I claim:—

In combination with a vessel open at one end and having a partition wall dividing the same into a pair of non-connecting compartments, a cap for the open end of the vessel, detachably secured thereto and having a partition to coact with that of the vessel and also having a pair of oppositely inclined covering portions each provided with an opening, one or more, the said cap being

further provided at its apex, at opposite sides, with a pair of upwardly extending ears, a rod connecting the said ears, a pair of closures pivotally mounted on the said rod, the said closures being respectively adapted to operate on the respective inclined portions of the cap and being provided on their under sides with stopper projections to enter and close the said openings of said inclined portions of the cap, each of the said closures having a substantially U-shaped arm forming a lever, and springs on the said rod and acting to normally hold the said closures in closed position on the cap.

In testimony whereof I affix my signature in presence of two witnesses.

ERNESTO FUCHS.
